COMBINED COFFEE TABLE AND DUAL AQUARIUM UNIT

Jack Hiland, 23545 Brook Road,
Chatsworth, Calif. 91311

Filed Feb. 15, 1967, Ser. No. 5,824

Term of patent 14 years

(Cl. D30—11)

FIG. 2

FIG. 1 is a front perspective view of a combined coffee table and dual aquarium unit showing my design; and FIG. 2 is a rear elevational view thereof.

I claim:

The ornamental design for a combined coffee table and dual aquarium unit, as shown.
